UNITED STATES PATENT OFFICE.

MARTIN L. GALLOWAY AND VICTOR W. WHYMAN, OF ADAMS, NEBRASKA.

RIBBED PULLEY.

SPECIFICATION forming part of Letters Patent No. 685,680, dated October 29, 1901.

Application filed April 15, 1901. Serial No. 55,959. (No model.)

To all whom it may concern:

Be it known that we, MARTIN L. GALLOWAY and VICTOR W. WHYMAN, citizens of the United States, residing at Adams, in the county 5 of Gage and State of Nebraska, have invented a new and useful Ribbed Pulley, of which the following is a specification.

This invention relates to pulleys; and the object of the present improvement is to provide a pulley with ribs having such reverse angle from opposite ends toward and merging into a central circumferential swell that a belt will be prevented from slipping therefrom and be forced toward the center of the 15 pulley and also be checked in any tendency to slip around the pulley, whereby the speed of the belt or another similar pulley which it engages will always be uniform, especially in machinery under a heavy strain of a variable character, another advantage being particularly apparent where a small pulley is driven by a larger one, both embodying the ribbed construction, and where a uniform speed is desired.

25 The invention consists in the construction and arrangement of the several parts, which will be more fully hereinafter described and claimed.

In the drawings, Figure 1 is a perspective 30 view of a pulley embodying the features of the invention. Fig. 2 is a longitudinal vertical section of the same. Fig. 3 is an end elevation thereof.

Similar numerals of reference are employed 35 to indicate corresponding parts in the several views.

The numeral 1 designates a hub, from which a web 2 extends to a rim 3 of any suitable extent provided with a central circumferential 40 swell or enlargement 4 of curved surface contour and from which the bearing-surface of the rim gradually slopes toward opposite ends, as clearly shown by Fig. 2. The bearing-surface of the rim which directly has 45 contact with the belt is formed with a plurality of regularly-spaced parallel ribs 5 and 6, extending completely therearound and arranged in reverse angles in relation to each other. The said ribs extend inwardly from 50 opposite ends of the pulley or the rim toward the center obliquely to the longitudinal axis of the pulley and vanish in the swell or en-

largement 4 at the center of the latter. The ribs also partake to a slight degree of the slope of the outer surface of the rim from the 55 swell or enlargement 4 toward the opposite ends of the rim, and said ribs also gradually decrease in vertical thickness or extent from the opposite ends of the rim toward the said swell or enlargement 4. It is proposed to form 60 the pulley of wood, metal, or other suitable material in large, small, and intermediate sizes and to apply it to all kinds of machinery and uses to which it is adapted. It is not necessary that the exact formation of hub and 65 web shown be used nor that the rim extend beyond the web, so long as the essential features are embodied in the construction, and which are the central swell or enlargement 4 and the ribs 5 and 6, disposed and arranged 70 as set forth.

The advantages of the improved form of pulley are manifold, and among many others may be particularly mentioned the prevention of slipping of a belt around the pulley, 75 because the ribs present obstructions of a positive nature to overcome any such tendency; that the belt-bearing surface of the rim does not have to be covered with some kind of antislapping material; that a belt will be prevented from laterally slipping off the pulley whether it be in direct alinement with the driven or driving device or not, because the belt will be drawn toward the center of the rim and overcome any lateral slipping force 85 exerted thereon, and that the speed of the belt and pulley will be maintained uniformly no matter what irregular strain the machinery with which the pulley is used is undergoing.

Many other advantages will become apparent to those using the improved device, and in view of the cheapness of manufacture of the device and the superior regular speed advantages it will be a valuable acquisition to the art.

Having thus described the invention, what is claimed as new is—

1. As an improved article of manufacture, a pulley having a rim with a belt-engaging surface having a central enlargement or swell 90 extending circumferentially thereof and oppositely-disposed reversely-arranged angular ribs extending inwardly to and merging into the said enlargement or swell.

2. As an improved article of manufacture, a pulley having a rim with a belt-engaging surface formed with a central circumferentially-extending swell or enlargement from which the said surface slopes downwardly toward the opposite ends of the rim, and ribs arranged in reverse angles to each other on opposite sides of and merging into the said swell or enlargement, the said ribs completely encircling the rim in regular-spaced parallel relation and having their vertical thickness

gradually decreased toward the said swell or enlargement.

In testimony that we claim the foregoing as our own we have hereto affixed our signatures ¹⁵ in the presence of two witnesses.

MARTIN L. GALLOWAY.
VICTOR W. WHYMAN.
